UNITED STATES PATENT OFFICE.

GILBERT VAN CAMP, OF GENEVA, JENNINGS COUNTY, INDIANA.

BREAST-YOKE.

SPECIFICATION forming part of Letters Patent No. 398,198, dated February 19, 1889.

Application filed September 4, 1888. Serial No. 284,541. (No model.)

To all whom it may concern:

Be it known that I, GILBERT VAN CAMP, a citizen of the United States, residing in Geneva township, in the county of Jennings and 5 State of Indiana, have invented certain new and useful Improvements in Breast-Yokes, of which the following is a specification.

The object of my said invention is to provide, to take the place of the ordinary neck-yoke, a "breast-yoke" which shall be adjustable in several directions, whereby certain advantages are obtained, as will be hereinafter more particularly described and claimed.

Referring to the accompanying drawings, 15 which are made a part hereof, and on which similar letters of reference indicate similar parts, Figure 1 is a perspective view of the forward end of the tongue or pole to a vehicle provided with a breast-yoke embodying 20 my said invention; Fig. 2, a horizontal sectional view on the dotted line 2 2 in Fig. 3, and Fig. 3 a vertical sectional view on the dotted line 3 3 in Fig. 2.

In said drawings, the portions marked A 25 represent the tongue or pole; B, the housing secured thereto; C, a joint-block connecting the breast-yoke to the pole, which is pivotally secured in said housing, and D the breast-yoke proper.

30 The pole may be the pole or tongue of any vehicle or implement and supports my improved breast-yoke upon its forward end, in the same location that the ordinary neck-yoke is commonly placed.

35 The housing B is made in two parts, and is firmly bolted onto the forward end of the pole A. It has flanges *a* at the sides where it fits onto the pole, in order not only to make flush what would otherwise be a groove where the 40 ordinary chamfer is on the pole, but also to make the union between the housing and pole more rigid and substantial.

The joint-block C is secured between the forward ends of the two parts of the housing 45 B upon a pivot-bolt, *b*. This pivot-bolt is surrounded by a sleeve, *c*, which is slightly longer than the thickness of said joint-block, and the two parts of the housing can thus be drawn up tightly by means of the bolt *b* 50 against the ends of this sleeve, and thus held firmly and rigidly in position without inter-

ferring with the horizontal movement of said joint-block on its pivot. This joint-block has a stem, *C'*, which extends out in front of the tongue and serves as a support for the breast-yoke proper. This stem is also surrounded by a sleeve, *c'*, and the nut *c²* can be drawn up tightly against the end of the sleeve without interfering with the pivoting of the breast-yoke on this stem, said sleeve being also 60 slightly longer than the distance through that portion of the breast-yoke through which it passes.

The breast-yoke proper consists substantially of a base and two arms, the base being 65 preferably a casting and the arms of ordinary gas-pipe bent into substantially the form shown. The stem *C'* passes through the base portion, as just described, and the arms extend out from the base on each side of this 70 stem to a proper distance to bring them in the proper position in front of the animals. They are preferably united by a cross-bar, *d*, which serves to stiffen them and bring the strain in turning on both the joints between 75 them and the base portion instead of, as would many times be the case, on one only. Upon the outer ends of the arms are preferably small castings *d'*, and these are formed to receive the breast straps or chains from the 80 harness of the animals. Staples *d²* are preferably provided for use with breast-straps, and rings *d³* serve better when breast-chains are employed.

All the castings used in this device, including 85 the housing, the joint-block, the base portion of the yoke, and the small castings on the ends of the arms, are preferably of malleable iron, while the arms themselves, as before stated, are generally gas-pipe.

90 This device is intended not only to swivel on the stem of the joint-block, but to move sidewise upon the pivot-bolt *b*, when desired, and provision has also been made to hold the device to one side or the other in either of the 95 positions indicated by the dotted lines in Fig. 2, to compensate for side draft, when it exists, which, as will be readily understood by those familiar with such matters, is often of considerable advantage. In order to provide for 100 these varying positions, including the holding of the device in line with the tongue when

desired, I have provided a hole in the rear end of the joint-block C, and a corresponding hole through the housing, through which a pin, b' , may be inserted, which will pass either through the hole in the joint-block C or to one side of it, as may be desired. It is sometimes desirable to allow a free movement of this device on its pivot, and in order to provide conveniently for all these varying conditions, and also to prevent dust and dirt from entering the hole for this pin, I have given said pin a peculiar construction. As shown most plainly in Fig. 3, the head is elongated, and is provided with a small lug or projection, b^2 , on its under side far enough from the pin proper to extend entirely beyond the joint-block C, and the housing has a second hole a corresponding distance from the hole in which the pin is ordinarily placed. When it is desired to permit the joint-block to move freely on its pivot, the pin is reversed and inserted in the second hole, while the small lug or projection fits into and stops up the upper portion of the first hole, as will be readily understood. When it is desired to have the stem in line with the pole, the pin is passed through the hole in the joint-block, as shown by the full lines. When it is desired to provide for side draft, the pin is placed in the same position; but the joint-block has first been moved to one side, as indicated by the dotted lines in Fig. 2.

Having thus fully described my said invention, what I claim as new, and desire to secure by Letters Patent, is—

1. The combination, in a breast-yoke, of a joint-block mounted pivotally in a housing upon the end of the tongue or pole, and the breast-yoke proper mounted and adapted to swivel upon a stem forming part of said joint-block.

2. The combination, in a breast-yoke, of a housing secured to the end of the pole, and a joint-block supporting the yoke mounted therein on a pivot-bolt, and a sleeve surround-

ing said pivot-bolt slightly longer than the thickness of said joint-block, substantially as described, and for the purposes specified.

3. The combination, in a breast-yoke, of a joint-block secured to the tongue, the stem portion of which extends through the base portion of the neck-yoke proper, said stem portion being surrounded by a sleeve slightly longer than the distance through the portion through which it extends, substantially as shown and described.

4. The combination of a breast-yoke adapted to move pivotally upon the end of the pole or tongue, and a pin whereby it may upon occasion be secured to position, said pin being provided with a small projection upon one side of its head, whereby by reversing said pin said movable portion may be either left free or secured rigidly in position and the openings for the pin at the same time kept covered, substantially as set forth.

5. The combination of the pole A, the housing B, the joint-block C, and the breast-yoke proper, D, said several parts being constructed and operating substantially as shown and described.

6. The combination of the pole, a housing thereon, and a breast-yoke secured in said housing, that portion which connects the breast-yoke to the housing having a rearward projection, and the housing having an opening larger than said projection, and a pin adapted to pass down through said housing and either through or alongside said projection, thus securing the breast-yoke either directly in line with the pole or to one side thereof, substantially as set forth.

In witness whereof I have hereunto set my hand and seal, at Indianapolis, Indiana, this 31st day of August, A. D. 1888.

GILBERT VAN CAMP. [L. S.]
